TUCKING MEANS FOR A WEB-WINDING MACHINE

Gerrit De Gelleke, Parsippany, N.J., assignor to Cameron Machine Company, Dover, N.J., a corporation of New York

Original application Jan. 17, 1961, Ser. No. 83,229, now Patent No. 3,134,553, dated May 26, 1964. Divided and this application Oct. 16, 1963, Ser. No. 316,692

3 Claims. (Cl. 242—66)

This application is a division of my copending application Serial No. 83,229, filed January 17, 1961, now Patent No. 3,134,553, dated May 26, 1964.

This invention relates to tucking means suitable for use in web-winding machines and, more particularly, relates to improved means for starting a leading end of a web around a rewind core in such a machine so that winding of the web material may be started without the necessity of using glue or other means for affixing the leading end of the web to the core.

Although the present invention may be employed with various types of winding machines, it is disclosed and described herein as employed in a winding machine and with roll-changing mechanisms all as disclosed in considerable detail in my copending Serial No. 821,395, filed June 19, 1959, now Patent No. 3,030,042, dated April 17, 1962, without, however, limiting this invention to its use with or as a part of that precise kind of winding machine.

It has been common practice, as a first step in machine winding of web material, that the leading end of the web be affixed to a rewind core in the machine, usually by using an adhesive of some kind. The principal object of the present invention is to provide satisfactory means for enabling such winding to be started on a rewind core without the need of using any adhesive or more or less equivalent affixing means.

In some winding operations it has been the practice to start the operation by very carefully setting up one or several turns of web material upon a rewind core in the machine without, however, using any adhesive. To accomplish this, it has usually been necessary for the leading end of the web to be very carefully tucked manually about the rewind roll; and, prior to this invention, satisfactory means for performing this tucking operation mechanically and automatically have not been developed. The present invention comprehends such mechanical means which, preferably, are automatic in operation.

The present invention employs an elongate tucking roller assembly which is supported in or on the machine in parallelism with the rewind core and which, while being maintained in parallelism with said core, may be moved toward the latter in order to cause a first roller of said assembly to engage a leading end portion of web material and press it against the core and to cause a second roller of said assembly to engage and press an adjacent part of said leading end portion against an adjacent winding drum of the machine. The arrangement is such that, when the core and drum are oppositely turned upon initiation of a winding operation by the machine, the leading end portion of the web, between the two rollers, will form a bight which will enter a nip area between the rewind core and the winding drum against which said core, with web material thereon, is in frictional driving engagement during a winding operation. As disclosed herein, the mentioned tucking roller assembly is supported in the machine for pivotal movement toward the rewind core but it will be obvious from the following detailed description that the tucking assembly need not necessarily pursue a pivotal or arcuate movement toward the rewind core but may, if desired, be arranged to pursue a straight-line movement into engagement with the leading end portion of the web

2

to press the latter against said core and the adjacent winding drum.

Without limiting this invention thereto, the present invention is disclosed herein as applied to a winding machine and roll-changing apparatus all as exhibited in my mentioned patent No. 3,030,042. The present disclosure details those parts of such a winding machine and roll-changing mechanism which cooperate directly with the tucking means comprehended by the present invention.

10 If details are desired additional to those set forth in this application, they may be obtained by reference to the mentioned patent No. 3,030,042.

In the accompanying drawings:

15 FIGURE 1 is an approximately central, cross-sectional view through various winding drums and rollers of a winding machine having therein a preferred embodiment of tucking means according to this invention; the parts of the winding machine which are shown including all parts which, in one way or another, coact quite directly with 20 the tucking mechanism, and this view shows all such parts as positioned approximately at the beginning of an operation of winding web material upon a new rewind core which has just been inserted in the machine.

25 FIG. 2 is an enlarged diagrammatic representation of certain parts of the mechanism illustrated in FIG. 1, the parts, however, being positioned as they would be shortly before the condition shown in FIG. 1, i.e., after a new rewind core has been inserted in the machine and before an intervening web portion between the new core and a 30 previously filled rewind core has been severed.

FIG. 3 is a view substantially along the lines of FIG. 2 but showing the various parts as they would be at the instant of severance of the mentioned intervening web portion.

35 FIG. 4 is a view substantially similar in general to FIGS. 2 and 3 but showing the various parts as they would be positioned shortly after severance of said intervening web portion and before the tucking mechanism is brought into play.

40 FIG. 5 is a view substantially similar in general to FIGS. 2—4 inclusive but showing a tucking assembly in position to tuck a severed leading portion of the web partially about a new rewind core so that, when a further operation of winding is started by the winding machine, said leading portion will wind about the core and, thus, enable a desired supply of web material to be wound upon the core.

FIG. 6 is an enlarged, horizontal sectional view substantially on the line 6—6 of FIG. 1.

50 FIG. 7 is an enlarged end view of the tucking mechanism and directly related parts of the winding machine as viewed directly oppositely to the views of FIGS. 1-5.

A general understanding of the winding machine, in which this invention is illustratively disclosed, may be gained from FIG. 1. A web W, issuing from a supply roll (not shown), moves, in the direction indicated by 55 arrows applied thereto, to a winding assembly consisting principally of an elongate front winding drum 20, and a generally similar, parallel, rear winding drum 22, one or both of these drums being power-driven.

60 In moving toward the winding assembly, the web is guided by guide or idler rollers 24, 26, 28, and 30 and, ordinarily, is processed in some manner, as, for example, by being slit by cutting engagement between a rotary mandrel 32 and a circular, rotary slitting knife 34, the purpose of the slitting being to convert the web from the form of a single broad web to plural, relatively narrow webs. As all these narrow webs are similarly handled by the disclosed machine, these webs hereinafter are referred to in the singular number.

65 Upon reaching the winding assembly, the web W first contacts the drum 20, passing in front of and over the

latter, thence under and almost completely around a new rewind core 36N between each of drums 20, 22 and said core which rests between and upon and, preferably, is held down upon said drums to derive winding rotation frictionally from the turning of the drums. In some circumstances, it is acceptable practice to have a light line of adhesive applied to the new core 36N so that a leading portion of the web will adhere to the core to facilitate the commencement of the operation of winding the web upon the core; but the present invention permits web winding without the need for applying adhesive to the new core.

The illustrated winding machine includes a horizontal, rotatable riding roll 38, borne at its ends in suitable bearings in similar carriages 40 having guiding portions 42, at their upper ends, slideable vertically upon and guided by stationary upright guide members 44 of the winding machine. Thus, the riding roll 38 may rise in continued riding engagement with the web material accumulating upon the rewind core 36. The carriages 40 and the riding roll 38 may also be raised and lowered independently of the rewind core 36 in a manner and for purposes hereinafter explained.

The tucking means, according to this invention, although capable of functioning quite independently of means, either manual or automatic, for changing cores in the machine, may be employed very advantageously to operate in conjunction with automatic core-changing means such as are disclosed, for example, in said Patent No. 3,030,042; and are illustrated and will now be described as utilized with the latter arrangement.

As may be understood in more detail from said patent, the core-changing mechanism comprises a pair of substantially similar unload arms 46 arranged to work similarly in unison by being keyed at their lower ends upon opposite ends of a horizontal rock-shaft 48 which is parallel to the axes of drums 20 and 22 as well as to several rolls in the machine. These arms are pivoted mechanically, through rocking of the rock-shaft 48 by crank means (not shown), between a "full-in" position and a "full-out" position.

Said "full-in" position of arms 46 is one in which slots 50, near the upper ends of said arms, underlie and are in vertical alignment with opposite end portions of a filled core (sometimes hereinafter referred to as a filled core or roll 36F) which, upon being filled by winding to the desired extent, has been raised by vertical lifters 52. These lifters are arranged to engage beneath opposite end portions of a filled roll 36F, when the latter is still in winding engagement with the drums 20 and 22, and lift said filled roll vertically to a sufficient extent that the ends of arms 46 and, more particularly, the slots 50 therein may pass leftwardly (as viewed in FIG. 1) to points directly below the ends of the filled roll to receive the latter when lowered thereinto. The lifters 52 have operating means (not fully shown) for raising and lowering them to lift a filled rewind roll 36F substantially from winding position and then to lower said roll into the slots 50.

In FIGS. 1-5, the arms 46 (only one being in view) are illustrated in what may be termed a "half-out" position which they may occupy throughout a tucking operation as hereinafter described. In a "full-out" position of the arms 46, they would be considerably rightward of the position in which they are illustrated in FIGS. 1-5, and in this "full-out" position a web-holding roller 54 is turned by a suitably driven wheel or roller 56 to press a trailing end portion 58 of the web tightly against an underlying turn of the web on the filled rewind roll 36F. This trailing end portion may have adhesive 60 applied thereto, in a manner hereinafter explained, to hold it securely to the underlying turn of the web.

The core-changing mechanism also comprises a pair of substantially similar load arms 62 (only one being shown in each of FIGS. 1-5) arranged to work similarly

5 in unison by being welded, keyed or otherwise fixed at their inner or lower ends upon opposite ends of a horizontal, tubular rock-shaft 64 borne upon rock-shaft 48 for rocking motion relatively to the latter's axis. The load arms are pivoted mechanically, in unison, through rocking of the tubular rock-shaft 64 by crank means (not shown).

10 Each of the load arms 62 is provided with a closable jaw 66 into which a new rewind core may be placed when the arms 62 are in their outer position as shown in FIG. 1, and said arms may then be pivoted counterclockwise, to their inner position shown in FIGS. 2 and 3, to move said new core into winding position upon the winding drums 20 and 22 after a previously filled core has been removed by the arms 46 from said winding position. In being moved to and from said outer position, an elongate brush 68, fixed to the two load arms 62, engages a glue-applying roller 70 to receive glue therefrom and apply it as at 60 to the trailing end of web on a filled rewind core 36F in a manner hereinafter described. An elongate knife 72 with a cutting edge 74 which, preferably, is serrated, is also fixed to the two load arms 62 and operates to cut the web at the end of a filled rewind roll 36F in a manner hereinafter described.

15 Tucking means according to this invention comprises an assembly comprising a pair of tucking rollers 76 and 78 preferably having surfaces of relatively high friction material such as, for example, rubber. These tucking rollers are carried in parallelism to the winding drums 20 and 22 and to a new or bare core 36N supported in winding position between and upon said drums. The tucking rollers are thus held by being mounted upon the lower end of a pair of similar, pivotal, suspension arms 81 which are keyed to opposite ends of a horizontal rock-shaft 80; and this shaft extends crosswise of the machine and is rockably borne at a position above the riding roll 38 in similar, suitable bearings in the two carriages 40 of the riding roll.

20 Each of the suspension arms 81 comprises an elbow 82 an upper part of which is keyed to the rock-shaft 80. A lower part of said elbow is formed with a groove 84 which, during a tucking operation, usually extends vertically or more nearly vertically than horizontally. The groove 84 extends into the upper part of the elbow 82 and preferably is open at both ends. Slidably mounted within the groove 84 is a slide member 86 an upper portion of which is provided with a longitudinal slot 88 through which extends a headed locking bolt 90 disposed non-adjustably within a suitable bolt hole in the lower portion of the elbow 82. A wing nut 91 or equivalent nut on bolt 90, when loose, permits the slide member 86 to be slid upwardly or downwardly to a desired adjusted position in groove 84, but said nut, when tightened, serves, with said bolt, to lock the slide member in such an adjusted position in a well-understood manner.

25 The tucking roller 76 is borne, at its ends, for rotation within suitable bearings at the lower ends of the slide members 86 while the tucking roller 78 is borne, at its ends, for rotation within suitable bearings in lugs 92, in closely spaced, side-by-side relationship to the roller 76. As best seen in FIG. 2, each lug 92 is secured tightly upon a related slide member 86 by a pair of headed bolts 94 which extend through a slot 96 and are threaded into the slide member approximately in the position shown in the drawing. The slot 96 is of such length that, when the bolts 94 are loosened, the lugs 92 may be shifted upwardly or downwardly to desired adjusted positions on the slide member 86 and they may, of course, be locked in such adjusted positions by tightening of said bolts.

30 During a tucking operation, the rollers 76 and 78 are in their positions, indicated in FIGS. 1 and 5, in which the suspension arms 81 are only slightly angular from freely suspended positions.

The suspension arms 81 and the tucking rollers, particularly roller 76, are arranged to function in connection with a related web-severing operation as well as for tucking purposes; and, for the web-severing purposes, the arms 81 must swing upwardly to some extent as indicated in FIGS. 2, 3, and 4. Cam means are provided, in association with one of the suspension arms 81, to achieve such upward swinging. These cam means comprise a cam plate 98 (FIG. 7) which is fixed to a side frame member 100 of the machine in a suitable manner as, for example, by a bracket 102 which, in turn, is suitably fixed to said frame member as, for example, by bolts 104.

The cam plate 98 has two cam surfaces 106, 108. To afford some latitude in the disposition of the cam plate 98 and its said cam surfaces, it is formed with a mounting slot 110 extending longitudinally thereof. The plate 98 is held upon the bracket 102 by a single nut-and-bolt arrangement in which a headed bolt 112 extends, preferably outwardly of the machine, through a washer 114 of greater width than the slot 110, thence through said slot, and, with a fairly accurate fit, through a suitable bolt hole in the bracket 102; and a nut 116 is threaded upon the end of the bolt 112, the arrangement being such that, when the nut 116 is loosened, the plate 98 may be slid upwardly or downwardly and/or angularly in relation to bracket 102. When the nut 116 is tightened, the plate 98 is held firmly in its adjusted position upon the bracket 102.

The cam means for swinging the tucking rollers 76, 78 upwardly include, also, a cam-follower plate 118 best seen in FIGS. 2-5 and 7. The plate 118 is arranged to operate as a bell-crank and it is pivotally mounted, at the juncture of its arms, upon the rock-shaft 80 in such manner as to be rotatable relatively to that shaft; hence, said plate is rotatable relatively to the suspension arms 81 which, as already stated, are constrained to turn with the shaft 80. The follower plate 118 is disposed at that end of shaft 80 which corresponds to the side of the machine upon which the cam plate 98 is mounted, and one arm of the plate 118 is provided with a cam roller 120 which operates as a cam follower on cam surfaces 106 and 108 of the plate 98.

Fixed upon the rock-shaft 80 and constrained to turn therewith is an arm 122 and, threaded through a lug 124 provided on plate 118 on the end of the latter remote from the roller 120, is an adjustable abutment screw 126 having thereon a lock nut 128 by means of which it may be locked in any adjusted position with reference to said lug. The abutment screw 126 is in the vertical plane of the arm 122 so that, during certain parts of a winding operation and, more particularly, of a web-severing and web-tucking operation, the upper end of the abutment screw 126 will abut a lower surface of the arm 122 and, when the cam-follower plate 118 is turned by cooperation with the cam surfaces 106, 108 as the riding-roll carriages 40 with the rock-shaft 80 move vertically, the cam-follower plate 118, through the mentioned abutment screw 126, operates to swing the arm 122 upwardly. That causes the shaft 80 to rock counterclockwise, as viewed in most of the figures of the drawings, and causes said shaft to swing the suspension arms 81 outwardly and upwardly from their positions, as in FIGS. 1 and 5, to other positions as shown, for example, in FIGS. 2-4. To hold the arm 122 yieldably against the screw 126, a coil spring 130 under tension is arranged with its opposite ends hooked to or otherwise secured to the arm 122 and to a rigid pin 132 fixed into the end of the follower plate 118 which is remote from the cam roller 120.

The lifters 52, for lifting a filled core from its winding position on the drums 20, 22, are similarly carried at opposite ends of the machine. Each lifter is pivoted at 135 (FIG. 1) in a vertically guided frame 137 connected to an above riding-roll carriage 40 by a lost-motion link rod 139. The lower end of the link rod is suitably con-

nected to the frame 137 by nuts 142 and extends upwardly, slidably through an integral lug 144 on the riding-roll carriage; and a collar 146 is adjustably fixed upon the link rod, above the lug 144, by a set screw 148. The lifters 52 cannot pivot downwardly from lifting position as shown in FIG. 1; however, they are capable of pivoting upwardly upon engagement with a subsequently inserted core, upon downward movement of the frame 137, to project under and later lift the latter core in a subsequent operation of the machine.

To understand the operation of the disclosed tucking means, not only for tucking purposes but also for co-operation with the knife 72 for web-severing purposes, it should be understood that, during a winding operation, the riding roll 38 rests upon the core 36N or, more properly, upon web material being wound upon that core so that, during the winding operation, the riding roll rises and, likewise, its carriage 40 rises with the principal parts of the described tucking means which are mounted thereon.

The mentioned rising movement occurs as a result of the increase in diameter imparted to the core by the accumulation of web material thereon. Then, when the desired amount of web material has accumulated on the core 36N, constituting the latter a filled core 36F, the drums 20 and 22 are stopped by stopping of the motors which turn them and, at about the same time, the riding roll 38 is lifted by means of suitable motors (not shown) which operate to pull upwardly on cables 134 which are fixed to the two riding-roll carriages 40 at opposite sides of the machine (only one such cable being shown in the drawing).

As the riding roll 38 is thus lifted from the filled core, continuation of such lifting causes the frame 137 and lifters 52 to be raised to engage the latter underneath opposite end portions of the core which protrude beyond the web material wound thereon; and further continued upward movement of the riding-roll carriages 40 causes the riding roll 38 and the filled core to move vertically upwardly in unison until said core is in a sufficiently elevated position that unload arms 46 may swing inwardly to bring their slots 50 directly underneath the ends of said filled core.

Immediately after the unload arms reach their inward position, the riding-roll carriages 40 and the related lifter frames 137 are motor-lowered to deposit the filled core in the slots 50. Then, the unload arms carry the filled core (now designated 36F), to an approximately half-out position as shown in FIGS. 1-5. Meanwhile, the load arms have moved to a full-in position in the machine and have deposited a new core 36N between and upon the drums 20, 22 in winding position, at which time the new core 36N and the filled core 36F are relatively positioned approximately as shown in FIG. 2; and the riding roll 38 and the tucking rollers 76 and 78, although somewhat lowered from their uppermost position, are, nevertheless, still somewhat above the new core as shown in said figure.

Further descent of the riding roll and the tucking rollers initiates the automatic tucking function of this invention now to be described. This further descent, caused by resumption of operation of the motor means for operating the carriages 40, causes the cam-follower plate 118 to be pivoted counterclockwise (as viewed in FIG. 2) by cam surface 106, the tucking rollers 76, 78, meanwhile moving downwardly and clearing the filled core 36F (the cam plate 98, of course, being in a proper adjusted position to provide such clearance); and then engaging the intervening portion of the web which extends between the core 36N and the filled core or rewind roll 36F to push that web portion downwardly, as in FIG. 3, into engagement with knife edge 74 to cut the web and into engagement with glue brush 68 to apply glue at 60, across the trailing end of the web on the filled core.

At about the time that the downwardly moving tucking

rollers reach their mentioned web-cutting positions, the riding roll 38 will have come to rest on the new core 36N and the core lifters 52 will have descended to similar lifting positions underneath the ends of the new core, pivoting upwardly as they move downwardly past the new core and then pivoting by gravity to their lifting attitudes as shown in FIG. 1, in condition to repeat a lifting operation, in the manner described, upon the overlying core after the latter has received its quota of web material.

After the web has been severed and while the various parts of the machine remain as illustrated in FIG. 3, the parts of the web assume positions somewhat as shown in FIG. 4. Immediately upon severance of the web, however, the operation of the machine is such that the load arms 62, having placed the new core in winding position, start swinging outwardly or clockwise as a result of which action they cause the suspension arms 81 to swing outwardly and upwardly, as indicated in FIG. 4, this swinging action occurring as a result of coaction of a cam member 136 fixed upon one of the load arms at one end of the machine and a cylindrical cam-follower surface 138 formed at a corresponding end and near the bearing of the tucking roller 76. This cam arrangement is such that the cam member 136, as the load arms 62 swing outwardly, raises the tucking roller 76 above and clear of the cutting edge of the knife 72, thereby avoiding possible damage to the knife or the tucking rollers at that stage of operation.

After the load arms 62 have moved outwardly to the extent that the cam member 136 clears the cylindrical cam-follower surface 138, the suspension arms 81 swing downwardly and inwardly by gravity and bring the tucking roller 76 down upon the then leading portion LW of the web which is about to commence being wound upon the new core 36N. In this manner, the tucking rollers 76, 78 assume tucking positions, as indicated in FIG. 5, in which roller 76 presses against a web portion which, in turn, is pressed against the new core 36N and tucking roller 78 rests upon a portion of the web nearer to its leading edge, which portion is held or pressed downwardly by the roller 78 against an underlying portion of web being fed to the machine around drum 20.

Up to this point, during the period following the completion of winding on the previously filled core 36F, the motors which drive the drums 20 and 22 during the winding operation are inactive and said drums are stationary. However, immediately after the engagement of the tucking rollers 76 and 78 with the several mentioned web portions and the consequent pressing of the latter against the new core 36N and the drum 20, a winding operation is resumed by starting of the motors which operate the drums 20 and 22. During the slow initial rotation of the drums and the new core 36N, the latter being frictionally driven by the drums, the tucking roller 76 is frictionally driven by the new core and the tucking roller 78 is frictionally driven by the winding drum 20, these rollers 76, 78, as a result, rotating in the directions indicated by the arrows applied thereto in FIG. 5.

It will be seen that at the commencement of a new winding operation and considering the rollers as viewed in FIG. 5, tucking roller 78, by rotating clockwise against the leading end of the web, tends to push that end of the web toward the core 36N, while tucking roller 76, by rotating counterclockwise against the web portion on the core 36N, tends to push the latter web portion downwardly. This urging of the web downwardly by roller 76 and inwardly or leftwardly by roller 78 induces the formation of a bight 140 in the adjacent portion of the web and, as the rotation of the winding drum 20 and new core 36N continues, the bight is forcibly tucked into place at a nip area between the core 36N and the portion of the incoming web which is moving from the drum 20 to said core. Once the bight 140 is thus tucked into place underneath the incoming web, it and the leading-

end portion of the web are held firmly against the core by the incoming web and continuation of the winding operation results in proper winding of the web material on the core without the need of using any adhesive.

As the new winding operation continues, the accumulation of web material on the new core 36N raises the riding roll 38 and its carriages 40, thereby causing surfaces 108 and 106 of cam plate 98 to swing and hold suspension arms 81, with the tucking rollers, outwardly through the medium of the cam-follower plate 118. Continued winding, roll changing, cutting, gluing, and tucking proceed in the manner already described.

It will be clear to those familiar with web-winding machines that the present concept relating to web-tucking means may be utilized in various ways other than herein disclosed without, however, departing from this invention.

I claim:

1. In web-winding apparatus comprising a rotatably driven, cylindrical, winding drum member, and a rewind core member supported in parallelism with and in frictional driving relation to said drum member to derive rotation therefrom to draw elongate web material through a nip area between said drum and core members at a web-receiving side thereof, and tucking means for pushing a leading web portion into said nip area at the start of a winding operation; said tucking means comprising a pair of spaced, parallel, tucking rollers, means supporting said rollers at said web-receiving side, in parallelism with said members, for engagement of said rollers with spaced parts of said leading web portion which rest upon said members; and said engagement being sufficiently forceful to cause the two tucking rollers to be driven oppositely by rotation of said members to push web material of said leading web portion, located between the latter's said spaced parts, toward and into said nip area.

2. A web-winding machine comprising a driven, cylindrical, winding drum member, a rotatable, cylindrical, rewind core member supported in frictional driving relation to said drum member to derive rotation therefrom to draw elongate web material through a nip area between said drum and core members at a web-receiving side thereof, and a tucking assembly comprising a pair of spaced, parallel, tucking rollers, and supporting means holding said rollers in separate, frictional driving relation to said core and drum members in position to press against said members at said web-receiving side with spaced portions of a leading web portion frictionally held between a first of said tucking rollers and said core member on the one hand and between a second of said tucking rollers and said drum member on the other hand; said tucking rollers thus being adapted to rotate oppositely in response to initial winding rotation of said core and drum members whereby to maintain such frictional holding of said leading web portion and to urge the latter into the form of a bight at said web-receiving side and adjacent to said nip area to facilitate entry of said leading web portion between the core and drum members.

3. A web-winding machine according to claim 2, said rollers being carried separately on members of said supporting means, which latter members are adjustably movable relatively to each other to position the two tucking rollers properly to separately engage said core and drum members.
